UNITED STATES PATENT OFFICE.

LEWIS M. PETERSON, OF GROVE CITY, MINNESOTA.

SILO.

1,215,983.

Specification of Letters Patent. Patented Feb. 13, 1917.

Application filed July 3, 1915. Serial No. 37,994.

To all whom it may concern:

Be it known that I, LEWIS M. PETERSON, a citizen of the United States, and a resident of Grove City, county of Meeker, and State of Minnesota, have invented certain new and useful Improvements in Silos, of which the following is a specification.

My invention relates to silos, and more specifically to that class thereof in which the lateral wall of the silo is formed of wooden staves.

The object of my invention is the production of a silo of this character which will be of durable and economical construction and efficient in use.

Other objects will appear hereinafter.

The invention consists in the combinations and arrangements of parts hereinafter described and claimed.

The invention will be best understood by reference to the accompanying drawings forming a part of this specification, and in which,

Figure 1 is a top plan view of a silo embodying the invention, a portion of the roof of the silo being broken away in order to expose underlying parts,

Fig. 2 is a horizontal section through the silo,

Fig. 3 is a section taken on substantially line $x-x$ of Fig. 1,

Fig. 4 is a detail section illustrating the fastening of the roof to the lateral wall of the silo,

Fig. 5 is a detail fragmental elevation of the upper end of the lateral wall of the silo illustrating the connection of the guy wires therewith, and

Fig. 6 is a detail section through the lower end of the lateral wall of the silo.

The preferred form of construction, as illustrated in the drawings, comprises a concrete foundation 1 upon which the lateral wall or shell of the silo is mounted. Said wall comprises a plurality of vertically extending wooden staves 2 arranged edge to edge in annular formation. Said staves are securely connected together at their lower ends by means of an annular connecting

member formed of a plurality of sections 3, each of said sections being angular in cross section with a vertically extending portion engaging against the inner side of the lateral wall and with an outwardly extending horizontal portion upon which the lateral wall rests, as clearly shown in Figs. 3 and 6.

Provided at adjacent ends of the sections 3 are ears 4 which are connected by turnbuckles 5 which obviously afford means of circumferentially adjusting the member 63 formed by sections 3. Also coöperating with the lower ends of the staves is an exteriorly positioned band 6 the ends of which are equipped with outwardly projecting ears 7 which are connected by a turn-buckle 8, 65 which also affords means of circumferentially adjusting said band, as will be readily understood. The band 6 and members 3 are connected together by transversely extending bolts 9 which project therethrough and 70 the intermediately positioned staves 2, as clearly shown in Fig. 6, nuts 10 being threaded upon the outer ends of said bolts. By this arrangement, it will be seen that the lower ends of the staves will be securely 75 clamped between the members 3 and 6. In order to permit of expansion and contraction because of changes in the temperature, the members 3 and 6 are provided with elongated slots at the points of engagement 80 therewith of the bolts 9, as clearly shown in Fig. 3.

Coöperating with the lower end of the silo shell are bolts 11, the lower ends of which are embedded in the foundation 1, as 85 clearly shown in Fig. 3. The upper ends of said bolts project upwardly from the foundation and upon said ends are arranged eccentric disks 12 for engagement with the peripheral portions of the sections 3. Nuts 13 90 threaded upon the bolts 11 coöperate with the members 12 to retain the same in clamping relation with the members 3. With this arrangement, it will be seen that the members 3 will be securely fastened to the foundation 1 in such a manner as to permit of 95 relative shifting in circumferentially adjusting the members 3.

The lateral wall of the silo is embraced at intervals by hoops 14 and arranged at the 103 upper end of said wall is a channel 15 which embraces the upper ends of the staves, as clearly shown in Figs. 3 and 4. The member 15 is formed of a plurality of sections which are adjustably connected by turnbuckles 16 which engage with outwardly projecting ears 17 provided at the ends of said sections, as clearly shown in Fig. 1. The channel member 15 is secured to the staves 2 by means of transversely extending 110 bolts 18 and coöoperating nuts 19, the opposite sides of said channel at the points of

engagement therewith of said bolts, being longitudinally slotted, as shown in order to permit of contraction and expansion, as mentioned above in connection with the 5 members 3 and 6.

- The sections of the channel member 15 are further secured in position by means of bolts 20 arranged immediately below the uppermost hoop 14 and secured in position 10 by nuts 21, as clearly shown in Fig. 4. To the outer ends of bolts 20 are pivoted upwardly extending members 22 which engage with corresponding bolts 18, being secured to the latter by the corresponding nuts 19. 15 With this arrangement, it will be seen that the sections of channel member 15 will be securely fastened so as to serve as a firm foundation for the roof which is connected therewith, as hereinafter set forth.
- 20 Provided at intervals upon the outer side of element 15 are exteriorly positioned loops 23 secured in position by corresponding bolts 18 and nuts 19. The loops 23 serve as means of connection with the upper end of the silo 25 of the guy wires 24, as clearly shown in Fig. 3.

Spaced around the upper side of element 15 are channel members 25 pivotally secured in position as clearly shown in Fig. 4, by bolts 26 and co-operating nuts 26'. The members 25 are adapted to embrace the outer ends of the rafters 27 of the roof 28 of the silo, being fastened thereto by means of bolts 29, as shown in the several views.

30 35 With this arrangement, it will be seen that the rafters 27 and hence the roof supported thereby will be securely fastened to the element 15 and hence to the upper ends of the staves 2.

40 While I have illustrated and described the preferred form of construction for carrying my invention into effect, this is capable of variation and modification without departing from the spirit of the invention.

45 I, therefore, do not wish to be limited to the precise details of construction set forth, but desire to avail myself of such variations and modifications as come within the scope of the appended claims.

Having described my invention what I 50 claim as new and desire to secure by Letters Patent is:

1. A silo comprising a lateral wall formed of vertically extending staves arranged edge to edge in annular formation; an annular 55 reinforcing channel embracing the upper edge of said wall for binding the upper ends of said staves together; a plurality of hoops embracing said wall at intervals; means for fastening said channel member to said staves, said means comprising bolts extending through said staves below the uppermost hoops; and members at the outer ends of said bolts extending upwardly therefrom for connection with said channel member, 65 substantially as described.

2. A silo comprising a lateral wall formed of vertically extending staves arranged edge to edge in annular formation; an annular reinforcing channel embracing the upper 70 edge of said wall for binding the upper ends of said staves together; a plurality of hoops embracing said wall at intervals; means for fastening said channel member to said staves, said means comprising bolts extending through said staves below the uppermost hoop; and members at the outer ends of said bolts pivotally connected therewith and extending upwardly therefrom for connection with said channel member, 75 substantially as described.

3. A silo comprising a lateral wall formed of vertically extending staves arranged edge to edge in annular formation; an annular reinforcing channel member embracing the 80 upper edge of said wall for binding the upper ends of said staves together; exteriorly positioned loops on said channel member; and guy wires connected with said loops, substantially as described. 90

In testimony whereof I have signed my name to this specification in the presence of two subscribing witnesses.

LEWIS M. PETERSON.
